REMOTE CONTROL FOR A PROJECTOR

Herbert T. Perkins, Grayslake, Ill., assignor to Bell & Howell Company, Chicago, Ill., a corporation of Illinois

Filed Dec. 20, 1960, Ser. No. 77,224

2 Claims. (Cl. 352—179)

This invention relates to a remote control for a projector, and more particularly to a gravity actuated selector switch for remotely controlling a motion picture projector.

An object of the invention is to provide a projector having a portable switch which may be turned as a whole to selected positions to control the operation of the projector.

Another object of the invention is to provide a portable switch unit having gravity actuated switch means the condition of which is determined by the gravitational position of the switch unit as a whole.

A complete understanding of the invention may be obtained from the following detailed description of a remote control forming a specific embodiment thereof, when read in conjunction with the appended drawings, in which:

FIG. 1 is a perspective view of a switch unit of a remote control forming one embodiment of the invention;

FIG. 2 is a perspective view of the switch unit in a position different from that shown in FIG. 1;

FIG. 3 is an end view of the switch unit;

FIG. 4 is a sectional view taken along line 4—4 of FIG. 3; and

FIG. 5 is a diagrammatic view of a motion picture projector control circuit including the switch unit of FIG. 1.

The invention provides a remote control for a projector in which a switch unit may be manually rotated as a unit to actuate gravity switch means to selected positions to control, for example, the operation of a motion picture projector connected thereto by an electric cord. Preferably the switch unit includes a rectangular case carrying two gravity actuated switches disposed at a right angle relative to one another in such relative positions that when the case lies on one side thereof both switches are open, when the case lies on a second side thereof one switch is open and the other closed, when the case lies on a third side thereof the one switch is closed and the other open and when the case lies on the fourth side thereof both switches are closed. Thus, the user of the switch may operate it needing only turn the case to present the desired side in the upward position.

Referring now in detail to the drawings, FIGS. 1 and 2 illustrate a manually movable remote control switch unit 11 in two of four positions of operation. The switch unit includes a case or housing 12 of a pair of molded, interfitting sections 12a and 12b of electrical insulation. The section 12a has known switch mounting brackets or spring clips 12 and 14 fixed to a plate portion 12c by screws 15, and the spring clips hold a pair of gravity actuated switches 16 and 17 in positions extending at 90° relative to one another and at 45° relative to sides or faces 12d, 12e, 12f and 12g of the case. When the switch unit is placed manually in its "STILL" position in which it rests on its face 12f (or has the face 12f facing downwardly), both switches 16 and 17 extend downwardly from their adjacent ends and mercury pools 16a and 17a close or bridge pairs of fixed switch contacts 16b and 16c and 17b and 17c, respectively. When the unit 11 is placed manually in its "OFF" position in which the face 12d faces downwardly, both switches 16 and 17 extend partially upwardly from their adjacent ends as illustrated in full lines in FIG. 5 and are open. When the unit is placed in its "REVERSE" position in which the face 12e is downward, the switch 16 is closed and the switch 17 is open. When the unit is located in its "FORWARD" position in

2

which the face 12g is downward, the switch 16 is closed and the switch 17 is open.

As shown in FIGS. 3 and 4, the two generally triangular case sections 12a and 12b are secured together by screws 21 threaded into the plate portion 12c and lock a pyramidal or funnel-shaped cap member 12h in annular groove 12i. The member 12h is of electrical insulation and is translucent, and a neon lamp 22 is fixed by cement 23 in central bore 12j in externally threaded stem 12k. A cap-like handle or knob 12l is threaded onto the stem. Decorative bands 23 are secured to the sections 12a and 12b. The bulb is electrically connected to the output of a transformer 24 mounted in the case with its primary connected between insulated conductor 25 of flexible, jacketed cord 27 and insulated conductors 26 and 28 through switches 16 and 17. The cap member has indicia 29 printed or engraved in the four faces thereof, the upwardly facing indicia indicating the position of the unit. When the small lamp 22 is illuminated, the light therefrom causes the cap member 12h to glow and the indicia to be readily seen.

To operate a motion picture projector in the forward direction, the user, who may be remote from the projector, turns the switch unit 11 from its "OFF" position as shown in full lines to its "FORWARD" position in which the face 12g of the case 12 faces downwardly, the switch 16 being open and the switch 17 being closed. The switch 17 closes the circuit to control relay 31 (FIG. 5) of a control circuit 32 mounted in the projector itself. A low voltage (below thirty volts) then is supplied to the winding of the relay 31 from a secondary winding 33a of a fan motor 33 of the shaded pole type having a main winding 33b, which in addition to driving the motor acts as a primary winding relative to the winding 33a, armature 33c and the usual stator of the motor serving as the core for transformer action therebetween. A power cord 34 is assumed to be plugged into a 110 volt alternating current power supply. The closed circuit to the relay 31 from the power supplying winding 33a also includes in series with the relay winding primary winding 24a of the low power step up transformer 24 and contact 35a and contactor 35b of manually operable, remote control overriding, selector switch 35 located at the projector itself, the switch 35 being set in its "OFF" position, as shown in FIG. 5, for remote control of the projector. The relay 31 pulls in to close contacts 31a, 31b and 31c and open contacts 31d and 31e. This operates in the forward direction a known projector driving motor 36 through a circuit from the power cord 34 including field winding 36a, speed controlling variable resistor 36b, the contacts 31a, armature 36c, the contacts 31b, and normally closed contacts 37a of relay 37. Until the film is threaded through the projector, a film actuated limit switch 38 is closed to contact 38a to light a room lamp plugged into receptacle 39 and power from the cord 34 is supplied to the room lamp through contacts 38a, 31c and 37b. Then when the film has been threaded through the projector it moves contactor 38b from contact 38a to contact 38c and holds it there to break the circuit to the room lamp and make the circuit to projector lamp 40 through autotransformer 41, switch 42 for varying the power to the lamp 40, the contact 38c, contactor 38b, and the contacts 31c and 37b. When the film runs out of the projector, the contactor 38b swings back to contact 38a, darkening the projection lamp 40 and relighting the room lamp.

For operation of the projector in reverse direction, the switch unit 11 is turned to its "REVERSE" position with the face 12e downward, the switch 35 being in its "OFF" position. In this position of the switch unit 11, the switch 17 is open and the switch 16 is closed to energize the winding of relay 37 through a circuit including the winding 24a, contacts 35a and power supplying winding

33a. The relay 37 then opens the contacts 37a and 37b and closes contacts 37c, 37d and 37e. The contacts 37c make the circuit to the motor 36 to run in the reverse direction from the power cord 34 through the resistor 36a, the contacts 37c, the armature 36c and the contacts 37d and 31d. The relay 37 also makes a circuit to the film actuated switch 38 to light either the room light receptacle 39 or the projection lamp transformer 41, depending on the position of the film actuated switch 38, through the contacts 37e.

For "STILL" projection, the user turns the switch unit 11 to its "STILL" position in which the face 12f is downwardly facing. In this position both the switches 16 and 17 are closed to energize the windings of both relays 31 and 37. Since both relays are energized, both contacts 31d and 37a are open and the film feeding and shutter driving motor 36 is de-energized, the blower motor continuing to run. The circuit to the film actuated switch 38 and the projection lamp 40 or the room lamp receptacle 39 is closed through both the sets of contacts 31c and 37e.

When the switch unit 11 is in its "OFF" position with the face 12d facing downwardly, both switches 16 and 17 are open so that the motor 36 and the projection lamp 40 are off, the room lamp is energized through 37b and 31e, and the blower motor 33 continues to run until the power cord 34 is disconnected from the power source.

The override switch 35 at the projector itself cuts off power to the remote control switch unit 11 whenever the user moves the contactor 35b from the contact 35a. To operate in the "FORWARD" direction, the contactor 35b is moved into engagement with contact 35d to energize the winding of relay 31. For "REVERSE" operation under the control of the switch 35, the contactor 35b is moved into engagement with contact 35c which prevents control by the remote control switch unit 11 and energizes the relay 37. For "STILL" operation, the switch contactor 35b may be turned to the next position from either of the contacts 35c and 35d to either contact 35e or contact 35f, respectively to energize both relays 31 and 37, a contactor 35g interlocked with the contactor 35b then being in engagement with either contact 35h or contact 35i which are interlinked with the relays 31 and 37.

The switch unit 11 is adapted to be used with a projector 51 (FIG. 2) having a known cord retracting device 52. The projector has a storage socket 52 for receiving the switch unit 11. The unit 11 has a keying or splining groove 12m in the face 12f which slides along keying rib 52a. The rib 52a prevents insertion of the unit 11 into the socket 52 except when the unit 11 is in its "OFF" position in which the face 12f is up. The retracting device resiliently pulls the cord 27 to urge the unit 11 into the socket 52.

The switch unit may be held manually and manipulated to the desired position or it may be placed on the floor, a table, chair, sofa or other like convenient location adjacent to the user and need be only rolled or turned to selectively operate the projector.

While the invention is thus described, it is not wished

to be limited to the precise details described, as changes may be readily made without departing from the spirit of the invention.

What is claimed is:

- 5 1. In a motion picture projector including a reversible electric drive motor, a projector lamp and a power source, the combination therewith of a first relay means operable when energized to connect the lamp to the power source and connect the reversible motor to the power source in a manner such as to run the projector in a forward direction, second relay means operable when energized to connect the lamp to the power source and connect the reversible motor to the power source in a manner such as to run the projector in a reverse direction, the first and second relay means being operable when both are energized to de-energize the motor and connect the lamp to the power source, a manually operable remote control switch unit including a pair of switches for selectively energizing only the first relay means, only the second relay means, and both the first and second relay means, and to de-energize both the first and second relay means, and manually operable switch means located at the projector having a plurality of positions for controlling the relay means and having one position connecting the remote control switch unit to the relay means.
- 10 2. In a motion picture projector including a reversible electric drive motor, a projector lamp and a power source, the combination therewith of a first relay means operable when energized to connect the lamp to the power source and connect the reversible motor to the power source in a manner such as to run the projector in a forward direction, second relay means operable when energized to connect the lamp to the power source and connect the reversible motor to the power source in a manner such as to run the projector in a reverse direction, the first and second relay means being operable when both are energized to de-energize the motor and connect the lamp to the power source, a remote control switch unit including a manually rotatable case and at least a pair of switches carried by the case for selectively energizing only the first relay means, only the second relay means, and both the first and second relay means, and to de-energize both the first and second relay means, and manually operable switch means located at the projector having a plurality of positions for controlling the relay means and having one position connecting the remote control switch unit to the relay means.
- 15 30 3. In a motion picture projector including a reversible electric drive motor, a projector lamp and a power source, the combination therewith of a first relay means operable when energized to connect the lamp to the power source and connect the reversible motor to the power source in a manner such as to run the projector in a forward direction, second relay means operable when energized to connect the lamp to the power source and connect the reversible motor to the power source in a manner such as to run the projector in a reverse direction, the first and second relay means being operable when both are energized to de-energize the motor and connect the lamp to the power source, a remote control switch unit including a manually rotatable case and at least a pair of switches carried by the case for selectively energizing only the first relay means, only the second relay means, and both the first and second relay means, and to de-energize both the first and second relay means, and manually operable switch means located at the projector having a plurality of positions for controlling the relay means and having one position connecting the remote control switch unit to the relay means.
